UNITED STATES PATENT OFFICE.

HIRAM G. SEDGWICK, OF MILL VALLEY, CALIFORNIA, ASSIGNOR TO THE NATIONAL SAFETY APPLIANCE COMPANY, OF SAN FRANCISCO, CALIFORNIA, A CORPORATION OF CALIFORNIA.

TRAIN SIGNALING AND STOPPING SYSTEM.

1,232,859.

Specification of Letters Patent. Patented July 10, 1917.

Application filed October 30, 1913, Serial No. 798,251. Renewed March 1, 1917. Serial No. 151,815.

To all whom it may concern:

Be it known that I, HIRAM G. SEDGWICK, a citizen of the United States, and a resident of Mill Valley, county of Marin, State of California, have invented certain new and useful Improvements in Train Signaling and Stopping Systems, of which the following is a full and clear specification, reference being had to the accompanying drawings, in which—

Figure 1 is a diagram view of a portion of a road bed showing one manner of arranging the wiring and other apparatus of my system;

Fig. 2 is a similar view showing, as a continuation of Fig. 1, a portion of the adjacent block;

Fig. 3 is a diagram of a preferred form of arranging the devices for a single road bed magnet;

Fig. 4 is a similar view showing the preferred arrangement for energizing a pair of adjacent coöperative road bed magnets from a single battery; and

Fig. 5 is a view similar to Fig. 4 showing a simpler form of the wiring of the companion road bed magnets G and Y.

My present system is especially adapted for that type of system in which the signaling or train stopping devices in the cab are put into action through the medium of magnetism generated by a magnet of suitable construction on the road bed; for instance, my present invention has relation to that type of system covered by my former patent numbered 896,332, dated August 18, 1908, in which an electromagnet on the road bed is energized and the influence of this magnet so affects an armature on the passing vehicle as to operate a suitable signal or a train stopping device.

I have shown my present invention applied to the well known bonded-rail closed-circuit signal system, the track battery being shown at *a* and the main relay being shown at *b*, the blocks being as usual separated by insulated joints *c*. The main relay, as usual, is located at one end of the block, and the track battery is, as usual, located at the other end of the block, and the short insulated rail sections which I locate at different points in the length of the block are spanned by conductors *d*, so as to keep the circuit between the relay and the battery continuously closed.

From the relay *b* extends two line circuits, one (*e*) of which extends backwardly to the block next in the rear and the other one (*f*) of which extends forwardly into the block next ahead, crossing the track and terminating near the end of the block. When the main relay is deenergized the circuit *e* is opened by the release of an armature *g*, and the circuit *f* is opened by the release of an armature *h*. In each of the circuits *e* and *f* is placed a battery respectively lettered *i* and *j*. In each of the circuits *e* and *f* is arranged in multiple a series of auxiliary relays *k*, which are deenergized simultaneously with the main relay and serve to control the various electromagnets on the road bed. Assuming that a train has entered block A and is, therefore, moving toward the right, the main relay *b* at the far end of the block will break circuits *e* and *f* and thus deenergize the relays *k* in the block B just ahead and also in the block in the rear of block A. The road bed magnets in the block in rear will be so located as to influence the armatures of any trains attempting to get into block A from the rear, and the magnets in block B will be so located as to affect the armatures of any trains that may attempt to get into block A through block B.

I prefer locating a series of five electromagnets near the end of each block, these magnets being lettered respectively S', S, R, G, Y. The magnet S' is nearest the end of the block and is located adjacent to a pair of short insulated rail sections *l* and is connected to one of the relay devices by conductors *m*. The next magnet S is arranged adjacent a short rail *n* and is connected to an adjacent relay device by wires *o*. The next magnet R is similarly arranged in relation to an insulated short rail *p* which abuts the rail section *n* and this magnet R also is connected with its auxiliary relay mechanism by wires *q*. The magnets G and Y are arranged side by side and adjacent to a short insulated rail section *r* and are each connected to the same auxiliary relay device respectively by wires *s* and *t*. The magnets which are intended to coöperate with trains going to the right are preferably arranged all at the right of the center of the track and are located out of alignment with each other, so that each magnet will be so located

- as to operate or influence but one of a series of armatures carried by the train. In Figs. 1 and 2, k^x illustrates a diagram of the boxes in which relays k and other operating devices are housed. One set of armatures will be arranged at the right hand side of the train vehicle for coöperation with the series of magnets located to the right of the center of the road bed, while another set will be located on the other side of the center of the train vehicle for coöperation with the other set of magnets when the train is going tender first in the opposite direction. I have illustrated a preferred arrangement of armatures in a co-pending application serially numbered 733,162, but it will be understood that my present invention may be employed in connection with other armature arrangements.
- 20 The circuit arrangement which I prefer using in connection with magnets S' , S and R is illustrated in Fig. 3. The magnet circuit m includes a battery u , this circuit being constantly closed, and a resistance v being included in this circuit to reduce the flow of current to a small electromotive force, the idea being to keep the battery from deteriorating by non-use, and at the same time avoid any considerable consumption of battery power. The conductor m at one side of the resistance is connected by a wire w to a spring x carrying an armature y which is adapted to be attracted by a magnet z , said magnet being included in a local circuit a' , in which circuit is a local battery b' , and the terminals of which circuits connect to a contact c' and a lever d' .
- 40 The lever d' tends normally to gravitate to bring its carbon contact e' into contact with spring x , but it is normally held up out of contact by means of a magnet f' included in a circuit g' . In the circuit g' is included a battery h' and armature switch i' , the switch i' being normally kept closed by the aforesaid relay k . The conductor m at the other side of the resistance v is connected by a wire j' to a leaf spring l' , which spring normally tends to swing downwardly and carries at its end a carbon contact m' .
- 50 A wire n' connects armature lever d' to a lever o' pivotally mounted at p' directly under the spring l' and carrying a companion carbon contact q' . The upper end of lever o' is connected to the piston rod r' of a dash pot s' and said lever o' is mounted upon an actuating lever t' which is pivotally mounted adjacent to a magnet u' , one end of said lever t' serving as an armature for the magnet and the other end lying under 60 the lever o' .
- 65 The magnet u' is in a circuit e' which includes the main battery u and resistance w' and a switch lever x' , said switch x' being adapted to be opened when the dash pot plunger ascends and closed when the said

plunger descends. The circuit v' at the opposite sides of the resistance w' is connected by wires y' to the insulated rail and the rails at the opposite sides of the road bed.

When the wheels of a train vehicle pass the rail l the wheels and axle therefor together with wires y' will shunt resistance v' and thus energize magnet u' . This will jerk down the adjacent end of lever t' and cause the dash pot plunger to be thrown up. As the plunger moves upwardly the switch x' will be opened and the magnet u' de-energized. Lever t' will then fall by gravity to normal position and spring l' will begin to force the dash pot plunger and its connecting lever downwardly, the time required for this downward stroke being determined by the dash-pot structure. When the dash pot plunger completes its descent, switch x' will be closed and contacts $m' q'$ will be separated, thus destroying the connection between wires j' and n' which was made when the dash pot plunger was elevated. This operation will be gone through each time a train passes over the rail l , and it will be observed that energizing current from battery u cannot reach magnet S' until resistance v is cut out. When this resistance v is cut out (in the manner hereinafter set forth) the full strength of the battery u will pass to magnet S' and thus energize the same and put it in condition to operate the train-control devices on the train.

Should the block ahead be occupied, relay k will be de-energized and switch i' opened. This de-energizes magnet f' and will permit lever d' to gravitate until it rests on contact c' and its contact e' has made contact with spring x . When the circuit a' is thus completed magnet z will be energized and the spring x will be drawn tightly into contact with contact e' and thus insure a good contact and also insure the holding of the lever d' in its downward position. With the lever d' in its down position should a train attempt to pass over rail l the operation of the parts will be the same as above described, except that resistance v will be cut out and the current from battery u allowed to pass to the magnet S' , its course being as follows: from wire w , spring x , lever d' , wire n' , lever o' , contacts $q' m'$, spring l' , wire j' , to magnet wires $m m$ at the opposite side of resistance v . The current will flow through these parts during the time the contacts $q' m'$ are in contact and this interval will be determined by the proportions of the dash pot and the power of the spring l' , as is evident. In this way I can provide for a suitable time interval for the energization of road bed magnet S' , so that at the end of the interval determined upon in constructing the apparatus the road bed magnet will be de-energized irrespective of the position of the train, thereby 130

permitting me to keep down the consumption of battery current to a minimum. It may happen at rare intervals that the train will stop in such position that it will bridge the rail l and the opposite rail; in this case, of course, the timing device will make repeated operations, but this will not be a serious objection, since the only result would be to waste a little current. It will be observed that the resistances w' and v permit a small quantity of current to constantly pass through their respective circuits, thus preventing deterioration of battery u by non-use and also tending to strengthen and preserve the power of the road bed magnet S' .

The stagger wires d may be arranged in the ordinary way, that is, as shown in Fig. 5, or they may be carried to the relay boxes k' and be provided with a switch a^2 , which will be opened when the plunger of the dash pot ascends. This switch will be needed only in case the rail l is sufficiently long to permit a train vehicle, such as a light locomotive, to stand on said rail without reaching over upon the adjacent ends of the main rails. Should a short train vehicle come to rest on this rail l it will be seen that the main rail circuit will close and thus set the signals and other control devices in the adjacent blocks at safety. This is avoided by providing a switch a^2 . As the rail l is connected to the main rail at the opposite side of the track bed, the plunger will be raised and thus keep the circuit through the stagger wire d broken.

In Fig. 4 I have shown the preferred wiring arrangement for the safety magnet G and the caution magnet Y , the object of this arrangement being to operate these two magnets with but a single battery u . The wiring for the magnet Y is the same as heretofore described for the magnets S' , S and R . The wiring for the magnet G is shown in heavy lines. It will be seen that the circuit S has one of its branches extended to include a resistance c^2 and an armature switch d^2 adapted to be held closed by the relay k . This circuit S is also connected to the levers l' and o' . With this arrangement, it will be seen that if the magnet k is energized, a passing train will bring contacts q' m' into contact in the manner hereinbefore described and thus cut out the resistance c^2 , permitting the full battery current to pass into magnet G and thus give the safety signal to the passing train. Should the magnet k be deenergized, the bringing together of the contacts q' m' cannot cut out the resistance c^2 , but will result in cutting out the resistance v , as heretofore described, and thus energize magnet Y for the purpose of giving a caution signal to the passing train.

In Fig. 5 I have shown a simpler form

of wiring for the companion magnets G and Y . In this arrangement, the dash pot or time interval circuit closing devices are done away with and in lieu thereof I provide a restoring device beyond the magnets adapted to be operated by the first vehicle in the train after it passes said magnets Y and G . With this arrangement, it is essential to employ at the opposite side of the track a short rail section similar to the insulated rail r , as shown.

With this wiring arrangement shown in Fig. 5, it will be seen that if the switch d^2 is closed, the passing train will cut out resistance c^2 through the wheels and axles and thus energize magnet G , but, should the magnet k be deenergized and the switch d^2 be opened and switch i' be closed, it will be seen that the passing train will cut out resistance v and thus energize magnet Y . It will be seen that the same wiring arrangement employed for the magnet Y may be employed for magnets R , S and S' if it be desired to do away with the dash pot restoring device illustrated in Fig. 3. At a point beyond the short rails r , I arrange another pair of short rails f^2 insulated from the rails r and the main rails. In the conductor Y is arranged a normally closed armature switch g^2 . This switch is adapted to be opened by a magnet h^2 which is adapted to be energized by an axle and wheels passing over the rails f^2 , this being accomplished by arranging said magnet in a circuit i^2 including a resistance j^2 and a battery k^2 , this circuit being connected to the rails f^2 at points on opposite sides of the resistance, so that the wheels and axle will cut out the resistance j^2 and allow the full current to pass into the magnet h^2 and thus open switch g^2 . This opening of the switch g^2 will open the circuit which was closed by the wheels and axles of the train and thus restore all the parts to normal, whether or not all the wheels of the train have passed off the rail sections r . In this way, it will be seen that the battery u will be cut off from the magnets Y and G the instant the first pair of wheels of the train passes on to rails f^2 , thus resulting in great saving in battery current, it being understood, of course, that the rails f^2 will be placed a sufficient distance from the magnets Y and G to avoid deenergizing these magnets until their companion armatures on the train have gotten past the magnets.

Having thus described my invention, what I claim as new and desire to secure by Letters Patent is—

1. In a system of the class set forth, a main relay and two series of auxiliary relays controlled by the main relay, one series being arranged in the block ahead and the other being arranged in the block behind, an electromagnet controlled by each of said

- auxiliary relays, said electromagnets being arranged on the road bed in staggered relation, the set or series in the block ahead being arranged at one side of the center of the track and the set or series in the block behind being arranged on the other side of the center of the track, whereby the several magnets at one side will each transmit a particular signal to the cab of a train going in one direction and the magnets on the other side will perform the same operation in the cab of the train going in the opposite direction.
2. In a system of the class set forth, a main relay and two series of auxiliary relays controlled by the main relay, one series being arranged in the block ahead and the other being arranged in the block behind, an electromagnet controlled by each of said auxiliary relays, said electromagnets being arranged on the road bed in staggered relation, the set or series in the block ahead being arranged at one side of the center of the track and the set or series in the block behind being arranged on the other side of the center of the track, whereby the several magnets at one side will each transmit a particular signal to the cab of a train going in one direction and the magnets on the other side will perform the same operation in the cab of the train going in the opposite direction, the first two magnets in each series being arranged side by side and means for alternately energizing the first two magnets.
3. In a system of the class set forth, a main relay and two series of auxiliary relays controlled by the main relay, one series being arranged in the block ahead and the other being arranged in the block behind, an electromagnet controlled by each of said auxiliary relays, said electromagnets being arranged on the road bed in staggered relation, the set or series in the block ahead being arranged at one side of the center of the track and the set or series in the block behind being arranged on the other side of the center of the track, whereby the several magnets at one side will each transmit a particular signal to the cab of a train going in one direction and the magnets on the other side will perform the same operation in the cab of the train going in the opposite direction, the track rails adjacent to each magnet being divided into insulated short rail sections and these respective short rail sections being electrically connected to the respective magnet circuits.
4. In a system of the class set forth, a short rail section insulated from the main rails, an adjacent magnet for actuating a signal or stopping device on a passing vehicle, a local battery and a resistance in normally closed circuit with said magnet, of

means for shunting said resistance and letting the full current through the battery, said means being controlled by a train in an adjacent block.

5. In a system of the class set forth, a short rail section insulated from the main rails, an adjacent magnet for actuating a signal or stopping device on a passing vehicle, a local battery and a resistance in normally closed circuit with said magnet, of means for shunting said resistance and letting the full current through the battery, said means being controlled by a train in an adjacent block, said means comprising conductors connected to said short rails and to the magnet circuit at opposite sides of the resistance and a relay operated switch in one of these conductors.

6. In a system of the class set forth, a pair of electromagnets adjacent each other on the road bed and each located so as to influence an armature on the train and means whereby a passing train energizes one or the other of these magnets according to whether the block ahead is occupied or not occupied.

7. In a railway signaling system, a pair of signaling magnets on the road bed, and means whereby a passing train energizes one or the other of said magnets according to whether the block ahead is occupied or not occupied, said means including a circuit for each magnet and a common battery for these two circuits.

8. In a system of the class set forth, a magnet on the road-bed for actuating a train control device on the train, a local battery for energizing this magnet and a resistance in circuit with the battery and the magnet to prevent the full current from going into the magnet, means for shunting the resistance operable by a passing train, and automatic means for restoring the resistance in a predetermined time after it is cut out.

9. In a device of the kind described, a track magnet, a line relay consisting of two magnets each of which is in a separate circuit, means controlled by one magnet for energizing the other magnet when the first mentioned magnet is deenergized, and means upon the energizing of the said second mentioned magnet to hold closed the track magnet circuit.

10. In a device of the class described, a track magnet, means for energizing said track magnet, a time limit relay, means for operating said time limit relay, and means controlled by said time limit relay to limit the period of time during which said track magnet is energized.

11. In a device of the class described, an insulated section of track, a time limit relay, means in circuit with said insulated section of track to control the time limit relay, a

track magnet controlled by said time limit relay, and means for energizing said time limit relay and track magnet.

12. In an automatic block signal system, 5 a plurality of blocks, a track relay in circuit with each block, a line relay in circuit with a source of electrical energy in one block and controlled by the track relay of the same block, a track magnet in each block, 10 and means controlled by said line relay for energizing said track magnet for a definite period of time.

13. In an automatic block signal system, a plurality of blocks, a track relay in circuit

in each block, a line relay in circuit with a 15 source of electrical energy in one block and controlled by the track relay of the same block, a track magnet in each block controlled by said line relay, a time limit relay comprising a magnet for controlling the 20 energizing of the track magnet.

In testimony whereof I hereunto affix my signature in the presence of two witnesses.
